FLUID PRESSURE CONTROL DEVICE

Johan A. Muller, Mount Gilead, Ohio, assignor to
 The Hydraulic Development Corp., Inc., Wil-
 mington, Del., a corporation of Delaware

Application September 9, 1938, Serial No. 229,216

4 Claims. (Cl. 60—52)

This invention relates to hydraulic machinery, and in particular to hydraulic devices and circuits for accurately controlling the pressures applied to workpieces by hydraulic machinery.

One object of this invention is to provide a hydraulic device and circuit for accurately controlling the maximum pressure applied to a hydraulic machine, such as a press, especially such a machine wherein the ram moves rapidly and comes to an abrupt stop.

Another object is to provide a hydraulic control device which, immediately upon the attainment of a predetermined pressure in the machine circuit, will automatically by-pass the pressure fluid discharged from the pump and at the same time set in operation the control mechanism which reverses the pump discharge, thereby eliminating the time lag previously occurring between the arising of the predetermined pressure and the operation of the pump control mechanism.

Another object is to provide a hydraulic control device which simultaneously by-passes the pump discharge and operates a limit switch for actuating the pump reversing circuit in response to the attainment of a predetermined pressure in the circuit to which the device is connected.

Another object is to provide a hydraulic press circuit including a pressing plunger, a reversible variable delivery pump and a hydraulic control device, interconnected by electrical and hydraulic circuits of such a nature that the control device automatically by-passes the pressure fluid discharged by the pump and at the same time effects the actuation of the pump reversing mechanism at the instant that a predetermined pressure arises in the circuit by reason of the action of the pressing plunger upon the work or devices being pressed by the press.

In the drawings:

Figure 1 is a central longitudinal section through the hydraulic control device of this invention, with the parts thereof in position prior to the attainment of the predetermined pressure.

Figure 2 is an enlarged sectional view of the lower portion of Figure 1, showing the parts shifted to by-pass the pump discharge and operate a limit switch in response to the attainment of a predetermined pressure.

Figure 3 is an enlarged sectional view of the upper portion of Figure 1.

Figure 4 is a diagrammatic view of a simplified circuit utilizing the hydraulic control device of this invention.

General arrangement

In general, the hydraulic control device of this invention consists of a spring-pressed valve plunger, which likewise carries a switch-operating cam. The valve plunger in one position cuts off intercommunication between two chambers,

one of which is connected to the fluid discharge line, such as to the fluid tank, whereas the other is connected to the pressure circuit, such as to the main cylinder of a hydraulic press. At a predetermined pressure the valve plunger overcomes the thrust of a spring and automatically shifts to by-pass the pressure circuit by opening communication between these two chambers. The valve plunger also carries a cam which actuates a limit switch at the instant the predetermined pressure is reached and the plunger is shifted, this limit switch controlling an electrical circuit which sets in motion the reversing mechanism of the reversible variable delivery pump used to supply fluid to the circuit and press.

Hitherto, one of the serious problems encountered by hydraulic engineers has been to accurately control the maximum pressure applied to or by a press, particularly where the pressing plunger moves rapidly and then comes to an abrupt halt. In many pressing operations the pressing plunger, under modern pressing conditions, is required to move at a comparatively rapid rate to insure efficient and economical production, yet at the end of this motion it engages a workpiece which yields but slightly. The pressing conditions frequently require that the pressure exerted by or against the pressing plunger shall reach a certain limiting pressure, and not exceed this pressure. For example, in coining operations the pressure must reach a certain value in order to satisfactorily form the details of the workpiece, yet must not exceed that pressure or the workpiece will be damaged.

Under previous arrangements for controlling this pressure, the pump control mechanism has been set so that it will be actuated when this maximum pressure is reached. In practice, however, a time lag occurs during which the pressure rises above the desired maximum pressure while the pump control is shifting to reduce the discharge of the pump. Setting the pump control to operate at a lower pressure to make an allowance for this overrun of pressure, gives no definite assurance that the required pressure will be reached, and the workpiece may therefore be insufficiently pressed.

Hydraulic control device

Referring to the drawings in detail, Figures 1 to 3 show the hydraulic pressure control device of this invention in longitudinal section. The device consists of a valve casing 10, having cylindrical chambers 11 and 12 separated by a narrow wall 13. Running through the valve casing 10 is a valve bore 14, having at its upper end an enlarged diameter portion 15. Passing through the wall 13 is a bore portion 16 of the same diameter as the bore portion 15. Beyond the chamber 12, however, the valve bore 14 has

a reduced diameter portion 17. Reciprocable within the valve bore 16 is a valve plunger, generally designated 18, and having a large diameter portion 19 and a small diameter portion 20 interconnected by a reduced diameter neck 21. Beneath the reduced diameter portion 20 the valve plunger 18 is provided with a stem 22, terminating in a reduced diameter threaded portion 23, carrying a threaded nut or collar 24, an internally threaded cam 25 in the form of a hollow collar, and a locknut 26 for locking the cam 25 in any desired position. The cam 25 is provided with an internal bore 27, which extends over the outer surface of the nut or collar 24.

Attached to the valve casing 10 at its lower end is a switch casing 28, carrying a normally closed pressure-responsive limit switch 29 having an operating member 30. A cover 31 at the end of the switch casing 28 gives access to the limit switch 29 and cam 25. Likewise secured to the valve casing 10 as by the screws 32 and within the limit switch casing 28 is an oil seal retainer 33, in the form of a collar surrounding the valve stem 22 and having an axial extension 34 serving as a spacer to limit the motion of the valve plunger 18. The threaded nut or collar 24 cooperates for this purpose with the spacer portion 34. Within the oil seal retainer 33 is an oil seal 35 surrounding the valve stem 22 to prevent leakage therealong. The valve plunger 18 is provided with a longitudinal bore 36, communicating with a cross bore 37 for draining leakage fluid from the leakage chamber 38 adjacent the oil seal 35. The chambers 11 and 12 are provided with threaded ports 39 and 40, serving respectively as inlet and outlet ports for the connection of the pressure and discharge conduits.

The upper end of the valve plunger 18, after passing through the bore portion 15, terminates in an enlargement or flanged cap 41 for receiving the thrust of one end of a coil spring 42. The coil spring 42 is mounted within a tubular spring casing 43, secured to the valve casing 10 by means of the bolts 44 and annular flange 45, a gasket 46 preventing leakage. The flange 45 is secured, as by welding, to the casing 43. The upper end of the spring casing 43 is similarly connected by similarly designated parts to the spring adjusting casing end plate 47. The latter is provided with a bore 48, within which is mounted an internally threaded collar or nut 49, as by the screws 50. The threads of the collar 49 receive a threaded adjusting stem 51, having an internal bore 52 for receiving the upper portion 53 of the upper spring cap 54, which receives the thrust of the upper end of the coil spring 42. A ball thrust bearing 55 is arranged between the spring cap 54 and the end of the threaded adjusting stem 51. Surrounding the latter is a spring adjusting casing 56, which with the end plates 47 and 57 forms a slippage chamber for receiving fluid which leaks into the space surrounding the stem 51. The spring casing 43 and the spring adjusting casing 56 are provided with threaded ports 58 and 59, to which are connected respectively the leakage conduits 60 and 61, which serve for draining off the leakage fluid.

The stem 51 terminates in an unthreaded portion 62, surmounted by a hand wheel 63, leakage being prevented by a packing 64 and gland 65, through which pass the threaded studs 66 engaged by the adjusting nuts 67. The spring adjusting casing 56 provides an oil-tight, dust-proof protection for the threads of the threaded stem 51. The threaded nut or collar 49 is in

bushing form so that it may be readily replaced. The plunger portions 19 and 20 are of slightly different diameters, this difference providing a differential plunger area which makes it possible to keep the spring 42 down to reasonable dimensions. By making the portion 19 of but slightly greater diameter than the portion 20, a comparatively small spring 42 may be used because it is on the area which represents the difference between these two diameters that the fluid pressure acts.

In the operation of the pressure control device of this invention the connection port 39 of the valve casing 10 is connected to the pressure chamber or pressure source, which has to be regulated as hereinafter explained. As the pressure builds up in the chamber 12 it tends to move the valve plunger 18 upward against the thrust of the coil spring 42 because the diameter of the portion 19 slightly exceeds the diameter of the portion 20. When sufficient force has been exerted by this pressure to move the valve plunger 18 upwardly a sufficient distance so that the portion 19 leaves the bored portion 16 in the wall 13, the pressure fluid from the chamber 12 passes through the chamber 11 and out through the port 40 to the discharge circuit. This instantly by-passes or unloads the discharge of the pump, thereby preventing the pressure in the circuit from going higher than the predetermined maximum pressure. At the same time the motion of the valve plunger 18 causes the cam 25 to engage and trip the switch member 30 of the normally closed limit switch 29, thereby opening the limit switch 29 and controlling an electrical circuit, which in turn, controls the pump discharge. The reduced diameter neck 21 between the valve portions 19 and 20 enables the flow of fluid to be materially increased. Since the cam 25 is adjustable independently of the coil spring 42, the action of the limit switch 29 can be advanced or delayed as required by the particular operating conditions.

By this invention, therefore, the entire discharge of the pump is by-passed when the desired pressure is reached and the press, or other machine which is controlled, cannot be subjected to more pressure than that for which the control device is set. Any leakage which occurs passes through the cross bore 37 and longitudinal bore 36, into the spring casing 43, whence it is drained off through the port 58 and drainage line 60.

Pressure-controlled hydraulic pressing circuit

In Figure 4 is shown a simplified pressing circuit including the control device, previously described and generally designated 70. Also included in the circuit is a hydraulic press, generally designated 71, a reversible variable delivery pump, generally designated 72, and shuttle valve, generally designated 73, a contactor switch, generally designated 74, a solenoid 75 for operating the pump control, and a manual switch 76 for initiating the operation of the circuit. The pump 72 is provided with a servomotor 77, by which the flow-control member of the pump is shifted to vary or reverse the delivery of the pump. A safety centering device 78 is also provided on the opposite side of the pump. The servomotor 77 contains a servomotor control valve operated by the valve rod 79 and lever 80 supported by the member 81. The lever 80 is connected by a link 82 to the bellcrank 83, the opposite arm of which is pivoted to

the armature 84 of the solenoid 75. The details of the pump 72, the servomotor 77 and the safety centering device 78 form no part of the present invention and are disclosed in the co-pending Ernst application, Ser. No. 170,250, filed October 21, 1937, now Patent No. 2,184,665.

Associated with the pump 72 is a tank 85 for containing the working fluid, such as oil. The pump 72 is connected by the conduit 86 to one end of the shuttle valve 73, the other end of which is connected by the conduit 87 to the conduit 88 leading to the upper port 89 of the main cylinder 90. The latter is provided with a main plunger 91 having a piston head 92 and a lower port 93, to which is connected the conduit 94 running back to the same pump connection 95, to which the conduit 86 is connected. The opposite pump connection 96 is connected by the conduit 97 to the conduit 88. The shuttle valve 73 is of a conventional type, having a shuttle valve member 98 reciprocable in the ports 99 and 100 of the partitions 101 and 102. The pipe 103 serves to discharge into the tank 85.

The shuttle valve member 98 is provided at its ends with enlarged heads 104 and 105, respectively. The conduit 88 is connected at its lower end to the inlet port 39 of the pressure control device 70, the outlet port 40 being connected by the conduit 106 to the tank 85. The conduit 60 is also connected to the conduit 106. The press 71 is provided with strain rods 107 interconnecting the main cylinder 90 with the press bed 108, upon which the workpiece is mounted together with suitable dies, molds or other apparatus depending upon the pressing conditions. The shuttle valve 73 is shown for purposes of simplifying the circuit in order to avoid the lengthy description required when a surge valve and main cylinder relief and by-pass valve are alternatively used in connection with the main cylinder 90. The shuttle valve 73 merely serves in a well known manner to compensate for the difference in fluid required by or discharged from the opposite ends of the main cylinder 90, due to the volume occupied by the main plunger 91.

In the operation of the circuit shown in Figure 4, it is assumed that the main plunger 91 occupies the retracted position shown. To start the main plunger 91 downward to initiate a pressing stroke, the operator closes the manual switch 76. This closes the circuit from the electrical supply lines 109 and 110, through the normally closed pressure-responsive limit switch 29 and the winding 111 of the conductor 74, closing the switch blades 112, 113 and 114 thereof. The switch blade 114 operates a holding circuit which maintains the energization of the contactor winding 111 when the manual switch 76 is released. The closing of the contactor switch blades 112 and 113 upon their contacts energizes the solenoid 75 and causes the armature 81 thereof to be drawn downwardly. This action shifts the bellcrank 83 and consequently the servomotor valve rod 79, causing the servomotor 77 to pull the flow-control element or shift-ring of the pump 72 to a position causing the pump to discharge pressure fluid through the conduits 97 and 88 and the port 89, into the upper end of the main cylinder 90, above the main plunger 91. At the same time the pressure passing through the branch conduit 87 acts against the shuttle valve head 104 and shifts the shuttle valve member 98 to the right, closing the left-hand end chamber thereof and opening the right-hand end chamber to communica-

tion with the tank 85 through the pipe 103. The pump then draws in fluid through the conduit 86 and shuttle valve 73, and discharges it through the conduits 97 and 88.

5 The main plunger 91 moves downwardly until it engages the workpiece, closes the molds, or does whatever work is required of it. The pressure resulting from this engagement of the main plunger 91 causes a consequent pressure to be built up within the main cylinder 90, this pressure being transmitted back through the conduit 88 and port 39 in the valve casing 10 of the pressure control device 70. When the pressure rises to the predetermined maximum for which the device 70 is set, the valve plunger 18 moves upwardly in the manner previously described, permitting the pressure fluid to be discharged through the valve chambers 12 and 11 and the port 40, into the discharge conduit 106 leading back to the tank 85.

At the same time the cam 25 on the valve stem 22 engages the limit switch member 30 and opens the normally closed pressure-responsive limit switch 29. This action deenergizes the circuit 25 between the lines 115 and 116, deenergizing the winding 111 of the contactor 74, opening the latter and deenergizing the solenoid 75 through its lines 117 and 118. The deenergization of the solenoid 75 permits a spring within the servomotor 77 to shift the valve rod 79 thereof in such a manner as to operate the servomotor and shifts the flow-control member or shift-ring of the pump 72 through its neutral position, into its reverse position. This reverses the discharge of the pump 72 and causes pressure fluid to be subsequently discharged through the conduit 94 and port 93, into the lower end of the main cylinder 90. At the same time, fluid is withdrawn through the port 89 and conduit 88 from the upper end of the main cylinder 90, and the shuttle valve member 98 shifts to the left into the position shown in Figure 4. This allows the fluid, which is pushed out of the main cylinder 90 by the rising plunger 91, to escape into the tank 85. This fluid is in excess of that handled by the pump 72 and forced by the latter into the lower port 93 of the main cylinder 90 to retract the main plunger 91.

As soon as the pressure drops in the conduit 88, the valve plunger 18 will be forced downwardly by the coil spring 42 within the pressure control device 70, releasing the switch-operating member 30 and causing the limit switch 29 to close. Since the winding 111 of the contactor 74 has been deenergized, however, nothing more will happen until the operator again closes the switch 76. In this manner it will be seen that the discharge of the pump 72 is by-passed by the fluid pressure control device 70 the very instant the main plunger 91 encounters a pressing resistance above the predetermined desired amount. This by-passing or unloading of the pump discharge relieves the pressure during the time lag period in which the pump servomotor 77 is reversing the delivery of the pump 72.

It will be understood that I desire to comprehend within my invention such modifications as come within the scope of the claims.

Having thus fully described my invention, what I claim as new and desire to secure by Letters Patent, is:

1. In a hydraulic press circuit, a reversible variable delivery pump having a pump flow-control element connected thereto, a main cylinder, a pressing plunger therein, a hydraulic

circuit interconnecting said main cylinder and said pump, and means responsive to the attainment of a predetermined pressure in said circuit for reversing the pump flow and for substantially simultaneously by-passing the entire flow of said pump during at least a portion of said reversing operation.

2. In a hydraulic press circuit, a reversible variable delivery pump having a pump flow-control element connected thereto, a main cylinder, a pressing plunger therein, a hydraulic circuit interconnecting said main cylinder and said pump, and means responsive to the attainment of a predetermined pressure in said circuit for shifting the flow-control element of said pump from a forward delivery position to a reversed delivery position and substantially simultaneously unloading the full discharge of said pump while said flow-control element is still in a forward delivery position.

3. In a hydraulic press circuit, a reversible variable delivery pump having a pump flow-control element connected thereto, a main cylinder, a pressing plunger therein, a hydraulic circuit interconnecting said main cylinder and said 25

pump, electrical means for shifting said flow-control element, and means responsive to the attainment of a predetermined pressure in said circuit for altering the energization of said electric means to shift said flow-control element through a zero delivery position and for substantially simultaneously unloading the discharge of said pump before said flow-control element reaches said zero delivery position during said shifting operation.

4. In a hydraulic press circuit, a main cylinder, a pressing plunger reciprocable therein, a reversible variable delivery pump connected to said cylinder and having a reversible pump flow-control member associated therewith for reversing the discharge of fluid from said pump to said cylinder for advancing and retracting said pressing plunger, and means responsive to the attainment of a predetermined pressure in said main cylinder for reversing the pump flow and for substantially simultaneously unloading the full discharge of said pump while said reversible flow-control member is being moved to its reversed position.

JOHAN A. MULLER.
